UNITED STATES PATENT OFFICE.

ABE THOMAS, OF CYNTHIANA, KENTUCKY.

JOURNAL-BOX.

No. 872,695.

Specification of Letters Patent

Patented Dec. 3, 1907.

Application filed July 13, 1906. Serial No. 326,124.

To all whom it may concern:

Be it known that I, ABE THOMAS, citizen of the United States, residing at Cynthiana, in the county of Harrison and State of Kentucky, have invented certain new and useful Improvements in Journal-Boxes, of which the following is a specification.

This invention consists of novel improvements in journal boxes for cars, and the 10 essential feature of the invention resides in the special construction of the box and inclosed bearing parts, together with the special lubricating mechanism arranged to lubricate the journal which is mounted in the box.

15 For a full description of the invention and the merits thereof and also to acquire a knowledge of the details of construction of the means for effecting the result, reference is to be had to the following description and 20 accompanying drawings, in which:

Figure 1 is a longitudinal sectional view through the journal box, showing a journal mounted therein. Fig. 2 is an end view of the box, the lid or closure for the same being 25 removed. Fig. 3 is a transverse sectional view through the box. Fig. 4 is a detail perspective view of the block which is mounted in the box beneath the journal. Fig. 5 is a 30 detail view of the bearing block bringing out more clearly the exact construction thereof.

Corresponding and like parts are referred to in the following description and indicated in all the views of the drawings by the same reference characters.

35 Specifically describing the invention the numeral 1 designates the outer casing of the journal box, one end of which is normally closed by a removable lid 2, while the opposite end is formed with the vertically elongated opening 8. Projecting through the 40 elongated opening 8 and extending within the interior of the journal box casing 1 is the journal end of the axle 3, the extremity of which is preferably provided with the usual 45 annular flange 4. Mounted within the journal box 1 and located over the journal 3 is a bearing block 11, the lower face of which is formed with suitable recesses having rollers 13 journaled therein, the said rollers having 50 direct contact with the journal 3 and serving to transmit the weight of the car body thereto. Opposite sides of the box casing are formed with internal ledges and the bearing block 11 is fitted between the said ledges and 55 the top of the box 1.

A plurality of oil cups 9 are located upon

the top of the box 1 and are arranged to deliver a lubricant to transverse grooves 10 formed in the upper face of the bearing block 11 toward opposite ends thereof. Leading 60 from the transverse grooves 10 to the recesses in the under face of the bearing block are the openings 12 which feed the lubricant to the bearing rollers 13 which owing to their contact with the journal 3 lubricate the same 65 evenly over its entire bearing surface. Removably mounted within grooves or guide ways formed in opposite side walls of the box 1 is a shelf 6 which serves as a support for the block 5 located under the journal 3 70 and formed with a longitudinal depression receiving the same, the inner end of the depression being enlarged and terminating in the reservoir or pocket 14 corresponding to the flange 4 at the extremity of the journal 75 3. This block 5 does not receive any of the weight carried by the journal and is normally spaced from the latter, merely serving to prevent the said journal from being thrown out of operative position with respect 80 to the rollers 13 by the jolting of the car or other analogous cause, and to form a pocket or reservoir for catching any lubricant which might fall from the bearing rollers 13.

Below the removable shelf 6 is a space 7 85 which may be utilized in any suitable manner, and which is necessary in order that the shelf 6 may be removed and the block 5 lowered when it is desired to remove the journal 3 from the box 1. In order to hold the 90 block 5 rigidly in position and to clamp it against the inner end of the box 1 a retainer bar 16 is employed, the extremities of which fit within curved grooves or ways 15 formed in opposite sides of the journal box. This 95 retainer bar 16 has a handle 17 attached thereto at an intermediate point, the said handle serving as a ready means for removing the retainer bar or inserting the same in 100 position.

Having thus described the invention, what is claimed as new is:

1. In a journal box, the combination of a casing, a bearing mounted within the casing, a journal received by the casing and engaging the bearing, a removable shelf mounted within the casing, and a guard block supported upon the shelf and normally spaced from the journal, the said guard block being designed to be lowered after the removal of 110 the shelf.
2. In a journal box, the combination of a

casing, a bearing mounted within the casing, a journal received by the casing and engaging the bearing, a slidable shelf arranged within the casing, and a guard block supported upon the slidable shelf below the journal and normally spaced therefrom, the said guard block being designed to be lowered upon the removal of the slidable shelf.

3. In a journal box, the combination of a 10 casing having ways formed at opposite sides thereof, a bearing mounted within the casing, a journal received by the casing and engaging the bearing, a sliding shelf arranged within the casing, a block supported by the 15 shelf below the journal and adapted to be lowered after the removal of the shelf, and a retainer bar having its ends received within the before mentioned ways and operating to

clamp the block against a side of the casing to prevent displacement of the said block. 20

4. In a journal box, the combination of a casing, a bearing block mounted within the casing, rollers journaled upon the bearing block, a journal received by the casing and engaging the rollers, a removable shelf arranged within the casing, and a block supported by the shelf below the journal and adapted to be lowered after the removal of the shelf. 25

In testimony whereof I affix my signature 30 in presence of two witnesses.

ABE THOMAS. [L. s.]
